UNITED STATES PATENT OFFICE.

LLOYD ALBERT SCHMUCKER AND ERNEST RALPH NORLING, OF SEATTLE, WASHINGTON.

DESIGN FOR A HANGER FOR WEARING APPAREL OR OTHER ARTICLE.

60,919.

Specification for Design.

Patented Apr. 25, 1922.

Application filed June 3, 1920. Serial No. 386,363. Term of patent 7 years.

To all whom it may concern:

Be it known that LLOYD ALBERT SCHMUCKER and ERNEST RALPH NORLING, citizens of the United States, residing at Seattle, in the county of King and State of Washington, have invented a new, original, and ornamental Design for a Hanger for Wearing Apparel or Other Article, of which the following is a specification, reference being had to the accompanying drawing, forming part thereof.

Fig. 1 is a front view of the hanger; Fig. 2 is a back view; and Fig. 3 is a side view of the same.

We claim:

The ornamental design for a hanger for wearing apparel or other article, as shown.

In witness whereof, we hereunto subscribe our names this 28 day of May A. D. 1920.

LLOYD ALBERT SCHMUCKER.
ERNEST RALPH NORLING.
